(57) **CLAIM**

The ornamental design for an animal toy, as shown and described.

DESCRIPTION

FIG. 1 is a top perspective view of the animal toy.

FIG. 2 is a bottom perspective view of the animal toy.

FIG. 3 is a front elevation view of the animal toy.

FIG. 4 is a back elevation view of the animal toy.

FIG. 5 is a left side elevation view of the animal toy.

FIG. 6 is a right side elevation view of the animal toy.

FIG. 7 is a top plan view of the animal toy.

FIG. 8 is a bottom plan view of the animal toy; and,

FIG. 9 is a sectional view taken along the line 9-9 in FIG. 7 of the animal toy.

The broken lines in the drawings depict portions of the animal toy that form no part of the claimed design.
